US0D1101310S

(12) **United States Design Patent** (10) **Patent No.:** **US D1,101,310 S**
(45) **Date of Patent:** **** Nov. 4, 2025**

(54) **DIRECTIONAL CONTROL DEVICE**

(71) Applicant: **Sharron Sanders**, Silverthorne, CO (US)

(72) Inventor: **Sharron Sanders**, Silverthorne, CO (US)

(**) Term: **15 Years**

(21) Appl. No.: **29/898,326**

(22) Filed: **Jul. 26, 2023**

(51) LOC (15) Cl. **30-04**

(52) U.S. Cl.

USPC **D30/153**; D30/156

(58) **Field of Classification Search**

USPC D3/7; D21/775; D30/151, 156, 153

CPC A01K 27/00; A01K 27/003; A61H 3/068

See application file for complete search history.

(74) Attorney, Agent, or Firm — Cramer Patent & Design; Aaron R. Cramer

(57) **CLAIM**

The ornamental design for a directional control device as shown and described.

DESCRIPTION

FIG. 1 is a left side elevation view of a directional control device, showing my new design;

FIG. 2 is a right side elevation view thereof;

FIG. 3 is a rear elevation view thereof;

FIG. 4 is a front elevation view thereof;

FIG. 5 is a top plan view thereof;

FIG. 6 is a top plan view thereof;

FIG. 7 is a close-up of the top plan view of FIG. 5; and,

FIG. 8 is a close-up top plan view of FIG. 6.

1 Claim, 3 Drawing Sheets
